UNITED STATES PATENT OFFICE.

PETER D. McLELLAN AND JOSEPH F. McKINNON, OF DORCHESTER,
MASSACHUSETTS.

APPARATUS FOR CLEANING HULLS OF SHIPS.

No. 834,399.

Specification of Letters Patent.

Patented Oct. 30, 1906.

Application filed November 21, 1905. Serial No. 288,480.

To all whom it may concern:

Be it known that we, PETER D. McLELLAN and JOSEPH F. McKINNON, citizens of the United States, residing at Dorchester, in the county of Suffolk and State of Massachusetts, have invented certain new and useful Improvements in Apparatus for Cleaning Hulls of Ships; and we do hereby declare the following to be a full, clear, and exact description of the invention, such as will enable others skilled in the art to which it appertains to make and use the same.

This invention relates to improvements in apparatus for cleaning the hulls of ships, and more particularly to a buoyant rubber and means for moving the same in contact with the hull to be cleaned.

The object in view is the provision of a cleaning device which may be passed in contact with the hull of a vessel without removing the vessel from the water, such cleaning device being constructed to readily conform to the contour of the part of the hull to which the same is contacting.

With this and other objects in view the invention comprises certain novel constructions, combinations, and arrangement of parts, as will be hereinafter more fully described and claimed.

In the accompanying drawings, Figure 1 is a diagrammatic view of a vessel with the present improved apparatus applied thereto. Fig. 2 represents a top plan view of one of the brushes, and Fig. 3 represents a longitudinal vertical central section thereof.

Referring to the drawings by numerals, 1 indicates generically a cleansing apparatus. (Seen in detail in Figs. 2 and 3 and in operative position in Fig. 1.) As many brushes 1 may be employed as desired, and the said brushes are preferably connected by suitable cable 2, passed beneath the keel of the vessel to be cleaned. Cables 3 engage the free ends of the brushes 1 and extend upwardly about the sides of the vessel in position to be grasped by the operator.

As seen in Figs. 2 and 3, each of the brushes 1 consists of a back 4, made up of a series of sections hinged together, as at 5, and each of said sections are provided with bristles 6 and scraping-plates 6' or other scraping and cleaning devices. It is to be

noted here that of course any form of scraper may be employed in connection with the sections 4 regardless of whether such scraper assumes the form of a bristle or a knife or other means for removing foreign substances from the hull of a vessel. To the rear of the sections 4 is secured an air-container 7, made of suitable flexible material, and a valve 8 communicates with the container 7 for controlling the admission or discharge of air to and from the said container. A suitable bail 9 may be connected with each of the end sections 4 for being engaged by the cables 2 and 3.

In operation as many of the brushes 1 may be connected up to the cables 2 and 3 as may be desired and the chambers 7 inflated. In the inflated condition the chamber 7 of each of the brushes is flexible and permits of flexible movement of the sections 4 with respect to each other, so that the rubbing or scraping device carried by said sections 4 may readily follow the contour of the hull of the vessel being cleaned. One of the cables 3 is drawn longitudinally, and the several cleaning apparatus 1 are thereby caused to engage the under face of the hull of the vessel by reason of the weight of the water tending to lift the buoyant brushes. Continued movement of one of the cables 3 in one direction will cause one of the brushes 1 to move downwardly to the keel of the vessel being cleaned, the said apparatus, owing to the flexibility of the bristle or other scraper support—to wit, the sections 4—following closely the several curves of the hull. The apparatus is further operated by drawing the other cable 3 longitudinally for bringing the brush, which has just descended to the keel, up toward the surface of the water, and by continued reciprocations of the brush the hull may be cleaned while the vessel remains intact and without dry-docking.

What we claim is—

1. A device of the character described, comprising a plurality of hinged sections, each section provided with a rigid scraper and a flexible brushing-surface, a flexible container secured to and covering the back or outer face of all of said sections, and a valve carried by said container.

2. A device of the character described,

comprising a plurality of parallel, hinged sections, a brushing-surface formed upon one side of each section, a rigid scraper secured to and extending longitudinally of each section, 5 bails secured to some of said sections, and a flexible container covering all of said sections and fixedly secured thereto, and a valve carried by said container.

In testimony whereof we affix our signatures in presence of two witnesses.

PETER D. McLELLAN.
JOSEPH F. McKINNON.
